2,105,588

FLOATING PARTITION

Clarke F. Davis, Short Hills, N. J., assignor, by
mesne assignments, to American Cyanamid &
Chemical Corporation, a corporation of Dela-
ware

Application April 29, 1933, Serial No. 668,490
Renewed August 3, 1937

4 Claims. (Cl. 72—46)

This invention relates to a floating wall or partition, that is, a wall not rigidly connected to other walls and/or a ceiling and/or a floor, but on the contrary one in which slight relative movement between the wall and one or more surfaces adjacent thereto is permitted.

Experience has demonstrated that with modern buildings, storms involving wind pressures set up vibration which is transmitted to all parts of the structure. This is true likewise in buildings having moving machinery or located above subways, train sheds or the like. As a result of this vibration, walls or partitions rigidly attached to the building walls or attached to other walls which are in turn rigidly attached to the building walls, receive this vibration, and are subjected to stress and unequal distortion. Consequently such walls have a tendency to crack and this may even go so far as to destroy the wall itself.

The principal object of the invention, therefore, is the provision of a vertical wall which will have a connection to other walls or surfaces of such a character as will permit relative movement therebetween so that in the event of building vibration or in the event of movement of the rigid walls and/or floor and/or ceiling of such building, the floating wall or partition will not be subject to these stresses with resultant cracking or destruction.

The invention is not particularly concerned with the material of which the wall or partition is made. This may be of metal or wood lath covered with plaster, partition tile of gypsum or the like, wall board, gypsum lumber or Plank or in fact any material which is subject to cracking either between the joints of the individual structural elements of which the wall is made, or otherwise.

A preferred embodiment of the invention consists in the use of angle irons or the like between the rigid wall and/or floor and/or ceiling and the floating wall or partition. It is desirable, of course, that one dimension of the floating wall be rigidly attached to something, and this rigid dimension is usually the floor, that is, the floating wall or partition may be rigidly connected to the floor of the room. The sides and top of such wall or partition are preferably enclosed between such angle irons, which in turn are rigidly attached to rigid walls and/or the ceiling, the sides and top of the floating wall or partition being spaced from the other walls. This permits of a sliding movement between the floating wall and the rigid walls so that in case of building vibra-

tions or other stress this movement will not transform itself into a distorting or disrupting force with relation to the floating wall.

The invention further contemplates that the floating wall shall be resiliently supported on the floor or the like to permit dissipation of any shocks which might otherwise be transmitted to the wall.

The invention further contemplates the use of decorative molding or angle irons which will to a great extent serve to mask their otherwise apparent purpose.

The invention further consists in the novel arrangement, combination and construction of parts more fully hereinafter described and shown in the drawings.

In the drawings—

Fig. 1 is a perspective view of a floating wall attached to rigid walls.

Fig. 2 is a sectional elevation of the floating wall of Fig. 1.

Fig. 3 is a horizontal sectional view of a floating partition.

Fig. 4 is an end elevation partly in section showing one method of locking a floating wall into position.

Fig. 5 is a side view showing a completed wall prior to the application of a finished material.

Referring now with particularity to the drawings and with reference to Fig. 3, the usual vertical columns of a building are shown at 1 encased in the usual plaster 2 or the like, between which a wall 3 extends.

These walls for the purpose of illustration may consist of elongated precast slabs of gypsum or the like 5, the opposite edges of which are provided with metal members 6 and 7 respectively, tongued and grooved to provide a mating interlock. This material is known in the trade as Gypsum Plank. This construction material is made in varying lengths and may be cut, sawed and spliced together to fit any desired space. As shown in Fig. 5, it is desirable that the horizontal joints between units be staggered with regard to each other, that is, that the horizontal joints between adjacent rows of units be out of register with each other. This makes for a stronger construction. While this form of material is shown as constituting a wall, yet obviously the invention is not limited thereto as any desired material may be used.

It will be apparent that the columns 1 and their encasing material 2 constitute the rigid portion of the building which will sway with the building. It is desirable according to this inven-

tion to permit relative movement between the wall 3 and the encasing material 2 of the columns. For this purpose angle irons 8 are provided on each side of the wall 3 rigidly attached 5 to the encasing material 2 but only frictionally engaging in a sliding joint the wall 3. It is to be noted that the end of the wall 3 is spaced from the encasing material 2 so that in case of movement the wall may accommodate itself between 10 the enclosed portions of the angle irons 8 and with relative movement to them and to the encasing material or the column as the case may be.

Reference to Fig. 4 will show that the wall 3 is supported in a saddle 9 having lower flanges 15 10 secured to the floor of the building as at 11. This saddle construction may be hollow to take electrical conduits 12, water pipes or the like, and may be provided at intervals with electrical outlets as desired, or may be entirely omitted if 20 desired. The construction of this saddle per se forms no part of the present invention.

It is desirable that this saddle be provided with upwardly projecting walls 13 between which a base 14 is situated which carries a substantial 25 layer of resilient material 15. This may be of a fibrous or rubbery nature and in fact of any material which will readily support the weight of the wall 3 in a resilient manner.

As thus described the wall 3 is to all intents 30 and purposes rigidly attached to the floor although resiliently supported thereon. When the wall 3 is swung into the position shown in the dotted lines and against angle iron 16 attached to the ceiling 17, a second angle iron 18 35 is affixed to the ceiling, the irons 16 and 18 holding the top of the wall 3 in a floating manner between the two. It is to be noted that the top of the wall 3 terminates short of the ceiling 17 so as to permit relative movement therebetween without disruption of the wall.

As shown in Fig. 4, the irons 16 and 18 may be of an ornamental nature and provided with a portion 19 which may be used as a picture molding or the like. This overcomes any tendency of the use of such angle irons to destroy the aesthetic effect in rooms in which they occur.

As shown in Fig. 2 the saddle 9 may take various forms and another modification is illustrated there conforming substantially to the principle 50 recited in connection with Fig. 4.

In Fig. 2 a modified form of angle iron for retaining the top of the wall 3 in place is shown to consist of a single piece of metal 20 having deformed downwardly projecting portions 21 between 55 which the wall 3 is secured and outwardly projecting flanges 22 secured to the ceiling as by nails 23. Such a retaining means is placed upon the wall before erection, the wall pushed into place and then the nails 23 driven into the ceiling.

A completed section of joining walls is shown in Fig. 1, which is thought to be self-explanatory.

Referring again to Fig. 3, it will be obvious, of course, that such floating walls may extend between rigid walls or parts of walls or a partition or wall may extend from a floating partition to another rigid wall or another floating partition, all within the scope of the invention.

While the invention has been shown and described with particular reference to certain instrumentalities, yet it is to be understood that the invention is not to be limited thereto but is to be restricted only by the scope of the claims.

I claim:

1. In combination, a floating wall extending 15 between two side walls, a ceiling and a floor, said wall being removably held by retaining means rigidly connected to said floor, retaining means rigidly secured to the side walls and the ceiling, the retaining means slidingly engaging 20 the floating wall, said floating wall consisting of individual building units, some of which are of less height than the height of the floating wall and interlocked together along their vertical edges by means of tongues and grooves, the horizontal joints between adjacent units being out of register.

2. The combination of claim 1 in which the 30 tongues and grooves of the individual units are of metal.

3. In combination, a floating wall extending 35 between two side walls, a floor and a ceiling, retaining means rigidly fixed to the side walls and extending a substantial distance there along, retaining means engaging said floor, said floating wall being carried by said means, retaining means between said ceiling and said floating wall, said floating wall being spaced from the side walls and ceiling, whereby said wall is permitted movement relative to the side walls, floor 40 and ceiling by sliding within the retaining means in which the wall consists of individual building units tongued and grooved together along their adjacent vertical edges.

4. In combination, a floating wall extending 45 between two vertical plane surfaces and two horizontal plane surfaces, all substantially at right angles to the plane of the wall, the wall terminating short of and being relatively movable with respect to three of said plane surfaces, 50 retaining means attached to three of said planes, the wall slidingly engaging said means, said wall consisting of individual units interlocked together along their vertical edges by means of 55 tongues and grooves, so that when the four planes are distorted with relation to each other, the distortion will not be communicated to the floating wall by reason of the sliding engagement between the wall and the retaining means.

CLARKE F. DAVIS. 60
